METHOD OF MAKING SHOES

Charles T. Anderson, Cincinnati, Ohio, assignor,
by mesne assignments, to The Littleway Proc-
ess Company, Boston, Mass., a corporation of
Massachusetts

Application August 8, 1935, Serial No. 35,338

9 Claims. (Cl. 12—142)

This invention relates to shoes and to the manufacture thereof and is illustrated herein with particular reference to shoes having flexible foreparts.

Objects of the invention are to provide improved methods of making shoes of the type referred to the practice of which is economical, simple and efficient and which will produce shoes that are light and flexible and yet strong enough to hold their shape during wear.

A preferred method of manufacturing shoes in accordance with my invention utilizes an insole comprising a thin flexible forepart reinforced with a stiff backing piece and a relatively thick and inflexible shank piece, the insole having ribs on its outer face to which a shoe upper may be secured to hold it in lasted position. The insole is mounted on a last with a shoe upper and the margins of the upper are secured in lasted relation to the ribs. As illustrated, the ribs are attached to the insole members by stitches and the margins of the upper are secured to the ribs by staples, the upper being first treated with cement by which it is to be permanently secured in lasted position.

After the cement has set the excess portions of the upper and ribs are trimmed, preferably inside the staples to remove them from the shoe bottom. An outsole is then laid on the shoe bottom and the last is removed from the shoe. The final steps in the process herein illustrated include removing the backing piece from the shoe together with the flexible forepart member, thereby leaving only one layer of sole material at the forepart of the shoe, and permanently attaching the outsole to the shoe bottom.

A variation of the method utilizes an insole of the above type but having a flexible forepart composed of material such as leather which is suitable to remain permanently in the shoe to serve as a support and cushion for the foot. As illustrated, the thin leather forepart member may be attached to a relatively thick and inflexible shank piece and a pair of lasting ribs secured to their outer faces by stitches. The thin leather forepart may then be reinforced by a relatively stiff backing piece such as fiber, leather board or the like, and mounted on a last with the backing piece against the last bottom. Since the rib-attaching stitches do not pass through the backing piece, it may be readily removed from the shoe after an outsole has been applied and the last has been withdrawn from the shoe. The outsole may be attached in any convenient manner to complete the construction of the shoe.

If it is desired to assemble the insole members including the backing piece first and then attach the lasting ribs, this may be accomplished, in accordance with another variation of the method, by reducing the width of that portion of the backing piece which extends rearwardly of the ball line of the shoe. The insole members may then be secured together, for example, by rubber cement and the ribs stitched on, the stitches rearwardly of the ball line lying outside the edges of the backing piece. After the outsole is laid or, if desired, is permanently attached to the shoe bottom by cement, the last may be removed and the loose rear portion of the backing piece grasped and pulled away from the thin leather member forming the forepart of the insole. In order that the backing piece may be separated from said member, however, it is necessary to sever the rib-attaching stitches forwardly of the ball line since these stitches pass through both the flexible forepart member and the backing piece. As herein illustrated, these stitches are severed during the trimming of the excess portions of the upper and ribs from the shoe bottom. It is within the scope of the invention, however, to break these stitches by other means or at a different stage in the construction of the shoe, for example, to cut through them with an abrasive during an upper roughing operation prior to laying the outsole.

With the above and other objects and features in view the invention will now be described in connection with the accompanying drawings and thereafter pointed out in the claims.

In the drawings,
Fig. 1 is an angular view of the members which form the insole of the present invention;

Fig. 2 is a plan view of the insole members united and having lasting ribs attached thereto;

Fig. 10 is a longitudinal sectional view of the shoe with the last removed illustrating the manner in which the forepart of the insole is removed;

5 Fig. 11 shows the forepart of the shoe after the outsole has been attached to the shoe bottom;

Fig. 12 is an angular view similar to Fig. 1 of insole members forming a modification of the invention;

10 Fig. 13 is a transverse sectional view of a shoe embodying the insole of Fig. 12 with the upper lasted and one side of the upper trimmed;

Fig. 14 is a longitudinal sectional view of the delasted shoe illustrating the manner of removing 15 the insole backing piece;

Fig. 15 is an angular view of insole members forming a second modification of the invention, the members being united and having lasting ribs attached thereto;

20 Fig. 16 is a transverse sectional view through the forepart of a lasted shoe embodying the insole of Fig. 15, one side of the upper being trimmed;

Fig. 17 illustrates the shoe after the outsole has 25 been attached by cement;

Fig. 18 is a longitudinal sectional view of the shoe delasted and the backing piece being removed therefrom; and

25 Fig. 19 is a transverse sectional view of a shoe 30 with the insole of Fig. 15 incorporated therein, the outsole of this shoe being attached by stitches.

In carrying out the method of the present invention there is provided a laminated insole similar to the type disclosed in Letters Patent 35 of the United States No. 1,947,031, granted February 13, 1934, on an application filed in the name of William H. Bain, and comprising a shank piece 30 of relatively thick and inflexible material such as leather, a forepart member 32

40 which is relatively thin and flexible and, as herein illustrated, is composed of paper or thin fiber board, and a thick and relatively stiff backing piece 34 preferably composed of fiber board or similar material. The shank piece 30 conforms 45 in outline to the periphery of a last bottom and extends approximately to the ball line of the last, the forward portion of the shank piece being tapered, as shown in Fig. 1 to prevent the formation of a ridge on the shoe bottom. The paper

50 forepart 32 conforms in shape to the periphery of the forepart of a last bottom and extends rearwardly to about the forward end of the shank portion of a shoe so that a considerable portion thereof will overlap the shank piece 30. The 55 fiber backing piece 34 conforms in outline to the flexible forepart 32 rearwardly to about the ball line, at which portion it is reduced in width to form a rearwardly extending tab 36.

As disclosed in the patent referred to, the 60 sole members are assembled in proper relation to each other and are secured together to form a complete insole 38 by adhesive, such, for example, as latex or rubber cement, the tab portion 36 of the backing piece being left free from 65 cement to facilitate its removal from the shoe, as will be hereinafter explained. After the insole members have been secured together to form a complete insole 38, strips 40 of fabric material, such as canvas, are secured along the margins of 70 its outer face from about the tip line to the heel breast line by stitches 42, these strips forming ribs to which a shoe upper may be secured in lasted relation to the insole. It will be noted in Fig. 2 that the edges of the narrow portion or 75 tab 36 of the backing piece are located inwardly

of the stitches 42 which secure the strips 40 to the insole so that the stitches do not pass through the tab.

In accordance with the method described in the patent mentioned, the completed insole 38 5 is molded and shaped to conform substantially to the longitudinal contour of the bottom of the last upon which it is to be mounted. The molded insole (Fig. 3) is then attached in the usual manner to the bottom of a last 44 with the fiber 10 backing piece 34 engaging the last bottom, as shown in Figs. 5 and 6. A shoe upper 46 comprising an outer layer and a lining, a doubler (not shown) being included if desired, is assembled on the last and pulled over, thus preparing 15 the shoe for the lasting operation.

The lasting operation, as herein illustrated, is performed in accordance with the method disclosed in Letters Patent of the United States No. 1,932,545, granted October 31, 1933, on an application filed in the name of George Goddu. As described in that patent the marginal portions of the upper 46 from the heel breast line to the ball line are coated at a convenient time prior to the lasting operation with either a water-dispersed rubber cement or, if desired, pyroxylin cement which, as herein illustrated, is applied to the inner side of the lining and is introduced between the plies of the upper. Forwardly of the ball line of the shoe pyroxylin cement is introduced between the plies of the upper but none is applied to the inner side of the lining. The cement on the inner side of the upper lining rearwardly of the ball line is indicated in Fig. 5 by the numeral 48 and the pyroxylin cement between 20 the plies forwardly of the ball line is indicated by the numeral 50 in Fig. 6.

As described in the Goddu patent referred to, the margins of the upper are seized by grippers (not shown) and worked over the margins of the shank piece 30 rearwardly of the ball line and up against the lasting ribs 40. Staples 52 are then inserted through the upper and ribs while the upper is held under tension, the staples being located just outside the plane of the central portion of the shank piece 30. Forwardly of the ball line the upper is worked over the margins of the flexible insole member 32, which is prevented from wrinkling or shifting position on the last bottom by the fiber backing piece 34, and the marginal portions of the upper are brought against the ribs 40 and secured thereto by staples 54, in the manner described above, the staples 54, as shown in Fig. 6, being located outside the plane of the paper or fiber forepart member 32. 45 The lasting operation at the sides of both the shank portion and the forepart of the shoe may conveniently be performed by the use of a staple lasting machine of the type disclosed in Letters Patent of the United States No. 1,796,451, granted 50 March 17, 1931.

The toe portion of the shoe may be lasted in the manner described above or it may be lasted with the aid of the bed-lasting machine, the margin of the upper in this case being held temporarily in overlasted position by tacks or by a toe binder of any well-known type. The heel-seat portion of the shoe may be lasted in any usual manner such, for example, as by tacks driven through the upper and shank piece 30 and 65 clenched against the shank piece by the metal plate on the bottom of the heel end of the last. The lasted upper is allowed to remain in the condition described for a period of time sufficient to permit the cement on its margins to set which 70 75

causes the portion of the upper rearwardly of the ball line of the shoe to become permanently bonded to the margins of the shank piece 30, and the margins of the upper forwardly of the ball line 5 to become stiff enough to remain in overlasted position without the aid of external means, such as the staples 54. The shoe is now ready for the trimming operation.

The trimming operation consists in removing 10 the excess portions of the upper 46 and ribs 40 to provide a relatively smooth surface for receiving an outsole. Around the forepart of the shoe from ball line to ball line, the trimming cut is preferably located inside the staples 54 and substantially 15 in the plane of the exposed surface of that portion of the upper margin which overlies the paper forepart 32. The cut is not located close enough to the plane of the forepart member, however, to sever the stitches 42 by which the 20 rib 40 is secured to the insole. Fig. 7 illustrates in section how one side of the shoe will appear after the trimming operation. The shank portion of the shoe may be trimmed in the manner just described although it is usually preferable to trim 25 the excess portions of the upper and rib outside the line of staples 52 so that the latter will remain in the shank portion of the shoe and thus afford a more secure attachment of the upper to the insole at this portion of the shoe. In either 30 case there will be sufficient space between the remaining portions of the ribs 40 to receive a usual shank piece or stiffener.

The next step in the method comprises severing the remaining portions of the strips or ribs 40 35 substantially at the ball line of the shoe to permit removal of the fiber backing piece 34 after an outsole has been attached to the shoe bottom. Fig. 8 illustrates this step of the process, the remaining portions of the ribs 40 being severed substantially 40 at the ball line by a knife 56. Care should be exercised in severing the ribs not to cut any substantial portion of the overlasted margins of the upper 46. After the ribs 40 have been severed in the manner described, an outsole 58 45 is coated at its margins with an adhesive 59 such as rubber cement or latex and is laid in the usual manner on the shoe bottom. Fig. 9 illustrates in section how the forepart of the shoe will appear after the sole-laying operation.

50 After sufficient time has elapsed to permit the sole-laying cement to dry, the last is removed from the shoe and the fiber backing piece 34 is pulled out. This is accomplished, as illustrated in Fig. 10, by grasping the loose tab 36 of the 55 backing piece and pulling the latter away from the outsole 58. Since the paper forepart 32 is secured to the fiber backing piece by cement, it will be removed with the backing piece except for such portions as may possibly have adhered to the upper as a result of cement penetrating the upper lining in the lasting operation. The portions of the trimmed lasting ribs 40 forwardly of the ball line will also come out of the shoe with the 60 backing piece and forepart member since these 65 portions are still secured to the forepart member and backing piece by the stitches 42, the rear portions of the ribs, which are secured to the leather shank piece 30, having been severed from the forward portions, as described above. Accordingly, the entire insole at the forepart of the 70 shoe is removed to expose the inner surface of the outsole surrounded only by the overlasted marginal portions of the upper. Since the overlasted margins of the upper have been stiffened by 75 the pyroxylin cement 50, they will retain the

shape of the last upon which they were formed and thus take the place of an insole at the forepart of the shoe.

The outsole 58 is rounded and channeled in the usual manner preparatory to being permanently attached to the shoe bottom and is then stitched to the shoe bottom by stitches 60, preferably lock stitches, to complete the construction of the shoe. The outsole attaching stitches 60 5 will, of course, pass through the overlasted margins of the upper and the shank piece 30 at the rear or shank portion of the shoe but will pass through only the outsole and stiffened margins of the upper at the forepart of the shoe. Fig. 11 10 illustrates the forepart of the shoe after the outsole has been stitched to the margins of the upper. Since there is only one thickness of sole at the forepart of the shoe, this portion will be extremely light and flexible. Moreover, since pyroxylin cement has stiffened the overlasted marginal portion of the upper at the forepart of the shoe, there will be no danger of such portion losing its shape and pulling away from the outsole. A usual slip sole can, of course, be inserted in the 15 shoe to cover the exposed margins of the upper 46. 20 25

Figs. 12 to 14, inclusive, illustrate a modification of the method for use in cases where it is desired to have a thin flexible insole member remain permanently in the forepart of the shoe to cover the overlasted margins of the upper and to provide a 30 cushion for the foot. As illustrated in Fig. 12, an insole is provided by initially cementing together in overlapping relation a relatively thick and inflexible shank piece 64 and a thin and very flexible forepart member 66 preferably composed of 35 leather such, for example, as upper leather or calfskin. The cement used in securing these members together is preferably a relatively light bonding cement such as rubber cement or latex, this being indicated in Fig. 12 by the numeral 68. 40 A pair of lasting ribs is provided on the outer face of the insole by securing thereto tapes or strips 70 by through-and-through stitches 72. A backing piece 74 of fiber or similar material, corresponding in outline to the forepart of the 45 insole and extending rearwardly to about the center of its shank portion, is now cemented to the inner surface of the thin flexible forepart member 66 by a light bonding cement such as latex. The rear portion of the backing piece 74 is preferably left free so that the removal of the backing piece from the shoe bottom at a later stage 50 in the method will be facilitated.

The insole is mounted on a last 76 with the fiber backing piece 74 engaging the last bottom and a shoe upper 78 is assembled on the last and pulled over. The margins of the upper in the present instance are coated with cement 79 between the plies and also on the inner side of the lining, the cemented area 60 extending entirely around the shank and forepart of the shoe and rearwardly to the heel breast line. The cement used in lasting the upper is preferably pyroxylin cement although other cements capable of producing a strong permanent 65 bond may be used if desired. The margins of the upper are worked over the shank piece and thin leather forepart 66 and are secured by staples 80 (Fig. 13) to the lasting ribs 70 in the manner described above. The excess portions of the upper and ribs are then trimmed off to provide a fairly even bottom surface for the reception of an outsole. At the forepart of the shoe the trimming cut is preferably located below the line of staples, as described above, to remove the latter 75.

from the shoe bottom while at the shank portion of the shoe the cut may, if desired, be located above the staples to permit them to remain in the shoe and thus afford a stronger attachment of the upper to the insole. Since the flexible forepart 66 is to remain in the shoe, the portion thereof inwardly of the trimmed edges of the upper margins and ribs may, if necessary, be covered with filler material 82 (Fig. 14) to level the forepart of the shoe for receiving an outsole. An outsole 84 is laid on the shoe bottom in the usual manner and, after the sole-laying cement has set, the last 78 is removed. The loose rear portion of the fiber backing piece 74 is now grasped and the backing piece is pulled away from the shoe bottom, this act causing the relatively light cement between the flexible forepart member 66 and the backing piece to be broken, thereby permitting removal of the backing piece without damaging the flexible member 66. Since the lasting ribs 78 at the forepart of a shoe are stitched only to the member 66 and the overlapping shank piece 84, these ribs and the stitches securing them will not interfere with the removal of the backing piece.

25 The outsole 84 may now be stitched permanently to the shoe bottom in the usual manner, the stitches passing through the flexible forepart member 66 and the overlasted margins of the upper at the forepart of the shoe.

30 Figs. 15 to 19, inclusive, illustrate a further modification of the method which may be preferred to the methods described above since it includes advantageous features of both. The insole of Fig. 15 comprises a relatively thick and inflexible shank piece 86 and a thin flexible forepart 88 of upper leather or similar material reinforced by a fiber backing piece 90, the insole members being secured together by rubber cement 92 and the backing piece being secured to 40 the forepart member 88 by similar cement 94. As illustrated in Fig. 15 the backing piece 90 is reduced in width from about the ball line of the insole to the rear end of the backing piece to form a tab 95, whereby the backing piece may be later 45 removed from the shoe. Lasting ribs 86 are stitched to the outer faces of the insole members 86, 88, the stitches 98 passing through the two thicknesses of materials at the forepart of the insole but lying outside the tab portion of the 50 backing piece rearwardly of the ball line of the insole.

55 The insole is mounted on a last 108 with the backing piece 90 against the last bottom and a shoe upper 102 including a lining is assembled on the last and pulled over in the usual manner. Pyroxylin or other suitable cement 103 is applied to the inner sides of the margins of the lining around the entire forepart and shank portions of the upper rearwardly to the heel breast line and the margins of the upper are worked over the shank piece 86 and the flexible forepart member 88 and secured in lasted position against the ribs 86 by staples 104. After the cement has set so that the overlasted margins of the upper are 60 permanently attached to the shank piece and forepart member 88, the trimming operation is performed to remove the excess portions of the upper and lasting ribs 86. As shown in Fig. 16, the trimming cut at the forepart of the shoe is made inside the line of staples 104 and, forwardly of the ball line, is preferably located close enough to the shoe bottom to sever the rib-attaching stitches 98. At the shank portion of the shoe, where the stitches 98 do not pass through the 65 narrow tab portion 95, the trimming cut may, if

desired, be located outside the staples 104 so that they will remain permanently in the shoe and thus strengthen the attachment of the upper to the insole. If the stitches 98 forwardly of the ball line are not severed during the trimming operation, they may be severed later by the roughing wheel during the upper roughing operation.

70 The margins of an outsole 106 are now coated with cement 108 such, for example, as pyroxylin cement which is allowed to dry. The portion of the shoe bottom extending between the trimmed margins of the upper is leveled if necessary by filler material 110, the usual shank stiffener is applied and, after the cement on the margins of the outsole has been activated by a solvent, the 15 outsole is located on the shoe bottom and pressed into permanent attachment therewith, this operation being conveniently performed, for example, with the aid of a machine of the type disclosed in an application for Letters Patent of the 20 United States, Serial No. 636,202, filed October 4, 1932, in the names of Milton H. Ballard, et al. After the attachment of the outsole, the last is removed from the shoe and the backing piece 90 is grasped by the loose tab 95 and pulled away from 25 the shoe bottom, as shown in Fig. 18. The act of pulling the backing piece 90 away from the shoe bottom separates the broken stitches 98 at the forepart of the shoe which have been severed either by the trimming or the roughing operation 30 so that the portions of these stitches located in the backing piece will be removed therewith. The cement bond 94 between the backing piece and the flexible forepart member 88 is not as strong as the bond resulting from the pyroxylin cement 103 35 which secures the margins of the upper in lasted relation to the flexible insole member 88 so that the backing piece 90 is easily broken away from its attachment to said insole member while the latter remains permanently attached to the overlasted 40 margins of the upper. Thus, a shoe is obtained similar to that previously described except that severed portions of the rib-attaching stitches 98 are removed with the backing piece 90.

45 The outsole 106 may, if desired, be attached to the shoe bottom by through-and-through stitches 112, as illustrated in Fig. 19, rather than by cement, these stitches being inserted after the last is removed and the backing piece 90 is pulled out. The stitches 112 will pass through the shank piece 50 at the rear portion of the shoe and through the margins of the upper and the thin flexible forepart member 88 at the forepart of the shoe, thereby insuring a strong attachment of the outsole without appreciably reducing the flexibility of the 55 shoe. The holes in the flexible forepart member 88, caused by the removal of portions of the rib-attaching stitches 98 with the backing piece may be covered by a usual slip sole inserted in the shoe bottom and cemented in place in the customary manner.

Having described my invention, what I claim as new and desire to secure by Letters Patent of the United States is:

1. That improvement in methods of making 65 shoes which consists in providing an insole comprising a thin flexible forepart, a stiff backing piece removably secured thereto and a relatively inflexible shank piece, attaching ribs to the outer face of the insole, securing a shoe upper in lasted 70 relation to said ribs, trimming off the excess portions of the upper and ribs, securing an outsole to the shoe bottom, and removing said backing piece and portions of the ribs secured thereto.

2. That improvement in methods of making 75

- shoes which consists in providing an insole comprising a thin flexible forepart member reinforced by a stiff backing piece removably secured thereto, a relatively inflexible shank piece and lasting 5 ribs attached to the insole, assembling the insole and a shoe upper on a last with the forepart backing piece engaging the last bottom, working the upper over the insole into lasted position against the ribs, securing the upper to the ribs with 10 staples, trimming off the excess portions of the upper and ribs, attaching an outsole, and delasting the shoe and removing said backing piece together with the forward portions of the ribs and the rib-attaching means.
- 15 3. That improvement in methods of making shoes having flexible foreparts which consists in providing an insole comprising a forepart of thin flexible material reinforced by a relatively stiff backing piece removably secured thereto, a shank 20 and heel portion of relatively thick inflexible material and strips attached to the outer face of the insole to form lasting ribs, assembling the insole and a shoe upper on a last with the backing piece engaging the last bottom, applying cement 25 for securing the upper in lasted position, working the upper over the margins of the insole and into lasted position against the ribs, inserting staples through the upper and ribs to insure that the upper will be held in lasted position while the 30 cement is setting, trimming the upper and ribs inside the staples after the cement has set thereby removing said staples from the shoe bottom, attaching an outsole to the shoe bottom, and thereafter delasting the shoe and removing said 35 backing piece together with the portions of the ribs and rib-attaching means which are secured thereto.
4. That improvement in methods of making shoes which consists in providing an insole having a forepart of thin flexible material reinforced by a relatively stiff backing piece cemented thereto, an integral shank and heel portion of relatively thick and inflexible material and ribs on the outer face of the insole, assembling the insole 45 with a shoe upper on a last, applying cement to the margins of the upper for holding them in lasted relation to the last bottom, securing the upper in lasted position against the ribs with staples while the cement is setting, trimming the 50 excess portions of the upper and ribs inside the staples after the cement has set thereby removing the staples from the shoe, securing an outsole to the shoe bottom, and delasting the shoe and removing the thin flexible forepart and the stiff 55 backing piece.
5. That improvement in methods of making shoes having flexible foreparts which consists in providing an insole having a forepart of thin flexible material reinforced by a relatively stiff backing piece cemented thereto, a shank and heel piece of relatively thick and inflexible material, and ribs on the outer face of the insole, assembling the insole with a shoe upper on a last, applying cement to the margins of the upper for holding them in lasted relation to the last bottom and the shank and heel piece, securing the upper in lasted position against the ribs with staples while the cement is setting, trimming the excess portions of the upper and ribs inside the staples after the cement has set thereby removing the staples from the shoe, laying an outsole on the shoe 60 bottom, delasting the shoe and removing the backing piece with the thin flexible forepart secured thereto, and permanently attaching the 65 outsole to the shoe bottom.
- 75

6. That improvement in methods of making shoes which consists in providing an insole comprising a forepart of paper reinforced by a relatively stiff fiber backing piece cemented thereto, a shank and heel piece of relatively inflexible leather, and strips stitched to the outer face of the insole to provide lasting ribs, assembling the insole and a multi-ply upper on a last with the backing piece engaging the last bottom, applying cement between the plies of the upper margins, 10 working said margins into lasted position over the insole and securing them with staples to the ribs to insure that the upper will be held in lasted position while the cement between the plies is setting, trimming the excess portions of the upper and ribs inside the staples after the cement has set thereby removing the staples from the shoe bottom, laying an outsole, delasting the shoe and removing the backing piece and the paper forepart, and stitching the outsole to the shoe 15 bottom.
7. That improvement in methods of making shoes which consists in providing an insole comprising a paper forepart reinforced by a relatively stiff backing piece cemented thereto and a shank 20 piece of relatively inflexible material, stitching strips to the margins of the insole to provide lasting ribs, the stitches being located inwardly of the edges of the backing piece rearwardly of the ball line of the insole, assembling the insole 25 and a shoe upper on a last with the backing piece next to the last bottom, applying cement for holding the margins of the upper in lasted position, working said margins over the insole and into lasted position against the ribs, inserting staples 30 through the upper and ribs to hold the upper in lasted position while the cement is setting, trimming the upper and ribs inside the line of staples after the cement has set thereby removing the staples from the shoe bottom, severing 35 the remaining portions of the ribs at the ball line of the insole, laying an outsole, removing the last and pulling out the backing piece with the paper forepart and the portions of the ribs forwardly of said ball line secured thereto, and attaching said outsole permanently to the shoe bottom. 40
8. That improvement in methods of making shoes which consists in providing an insole having a thin flexible forepart member and a relatively thick and inflexible rear portion, said forepart member being reinforced by a stiff backing piece removably secured thereto, stitching strips to the margins of the insole to form 45 lasting ribs, assembling the insole and a shoe upper on a last with the backing piece against the last bottom, applying cement to the margins of the upper for securing them in lasted relation to the insole, working said margins over the insole and securing them in lasted position 50 against the ribs with staples thereby holding the upper in lasted position while the cement is setting, trimming the upper and ribs inside the staples after the cement has set thereby removing the latter from the shoe bottom, breaking the strip-attaching stitches which pass through the backing piece, permanently securing an outsole to the shoe bottom, and delasting the shoe 55 and removing the backing piece but leaving the flexible forepart member in the shoe. 60
9. That improvement in methods of making shoes which consists in providing an insole having a forepart of thin flexible leather and a rear portion of relatively thick and inflexible leather, said forepart being reinforced by a backing piece 65
- 70
- 75

of relatively stiff fiber lightly cemented thereto, stitching strips to the margins of the outer face of the insole to serve as lasting ribs, the stitches being located outside the backing piece rearwardly of the ball line of the shoe, assembling the insole and a shoe upper on a last with the backing piece engaging the last bottom, applying a strong bonding cement to the inner sides of the margins of the upper, working said margins over the margins of the insole and into lasted position against the ribs, inserting staples through the upper and ribs to hold the upper in lasted position while the cement on its margins

is setting, trimming the excess portions of the upper and ribs inside the line of staples after the cement has set thereby removing the staples from the shoe bottom, said trimming cut passing through and severing the rib-securing stitches at the forepart of the shoe, laying an outsole on the shoe bottom, delasting the shoe, breaking the cement bond between the backing piece and the thin leather forepart, and pulling the backing piece from the shoe together with the portions 10 of the stitches which are located therein. 5

CHARLES T. ANDERSON.
